APPARATUS FOR PACKING EXPLOSIVE
IN CARTRIDGES

Joseph L. Clark, Wilmington, Del., Carlyle M. Linden, Chattanooga, Tenn., and Cloyd J. Ober, Bessemer, Ala., assignors to Hercules Powder Company, Wilmington, Del., a corporation of Delaware

Application May 25, 1942, Serial No. 444,456

3 Claims. (Cl. 86—29)

1

This invention relates to an apparatus for packing explosive in cartridges and, more particularly, to the packing of cartridges with semi-plastic explosive, so that the portion first packed is firm, the portion packed adjacent thereto is soft and the portion last packed is firm.

Heretofore, attempts to pack a portion of a cartridge firm and the remainder soft or to pack the entire cartridge soft have been unsatisfactory, due to the fact that the end or ends of the soft packed cartridges, mushroom, wrinkle and/or collapse.

The principal object of this invention is to provide an apparatus for packing cartridges wherein an intermediate portion of the cartridge is soft packed.

Another object of this invention is the provision of mechanism for effectively, safely, and expeditiously packing cartridges with a soft central portion.

Another object of this invention is the provision of automatic actuating mechanism for the tamp rods, whereby the difficulty of releasing accidentally stuck rods is eliminated along with the dangers inherent therewith.

Still another object of the present invention resides in rendering the tamping rods immediately inoperative whenever exigencies occur.

Other objects of the invention will appear hereinafter, the novel features and combinations being set forth in the appended claims.

This invention resides in a new and useful improvement comprising a triple-purpose dogging bar to be used in machines for packing explosive in cartridges and the particular embodiment of the invention is illustrated in conjunction with a Hall cartridge-loading machine similar to the machine disclosed in U. S. Patent No. 601,138 to H. P. Hall. Certain improvements in the Hall machine have been made from time to time, and the illustrations depict a Hall machine of recent origin, however, the fundamental principles disclosed in the above mentioned patent to Hall are still retained and are well known in the art. The present invention is described in conjunction with a modern Hall machine and is clearly understood in reference to the above mentioned patent.

Generally described, the present invention comprises apparatus for packing a cartridge with semi-plastic explosive in such a manner that the lower portion is firm, the central portion soft, and the upper portion firm. This method of packing is accomplished by a triple-purpose bar whose functions are: (1) to automatically cause

2

the tamp rods after they have packed a couple of strokes in the normal way, i. e. have firmly packed the bottom portion, to slip up and to then loosely pack the cartridge by merely pushing explosive into the cartridge without tamping, as the resistance of the explosive in the cartridge builds up, the tamp rods keep slipping up until the cartridge is full, thereby giving a cartridge having a soft packed central portion; (2) to provide a safety feature whereby the bar is automatically actuated between packing cycles to prevent any tamp rods from accidentally sticking down in such manner as to interfere with the rotation of the drum which carries the cartridges; (3) to provide a manually operated device which enables the operator to dog up the entire set of tamping rods to the inoperative position whenever accidents or other exigencies occur.

A preferred embodiment of the invention has been chosen for purposes of illustration and description and is shown in the accompanying drawings forming a part of the specification wherein like reference symbols refer to like parts wherever they occur:

25 Fig. 1 is a part front elevational view of the cartridge packing machine with a part of the revolving shell holder shown in section;

Fig. 2 is a sectional view taken on line 2—2 of Fig. 1;

30 Fig. 3 is a part rear elevational view of the triple-purpose bar;

Fig. 4 is an enlarged sectional view taken on line 4—4 of Fig. 3;

35 Fig. 5 is a fragmentary plan view of the triple-purpose bar and appurtenant actuating mechanism;

Fig. 6 is a transverse sectional view of the triple-purpose bar with an elevational view of a dogging element shown therewith.

40 In Fig. 1 and Fig. 2, A frames 1 are rigidly braced by tie-rods 3 and as an integral structure is supported by suitable sub-structure shown out of function. Driving means (not shown) drive gears 5 which engage gears 7 which have one end of connecting rods 9 pivotally connected thereto and the other end of the rods pivotally connected to a horizontal cross-head 11. The cross-head 11 reciprocates with an up and down motion as imparted by the connecting rods 9 and is in frictional engagement with a plurality of tamp-rods 13 thereby likewise reciprocating the plurality of tamp-rods. The tamp-rods 13 are preferably made in several sections and extend from the top of the machine, usually in an upper story down through the floor to a story below,

and the operating devices for the tamp-rods and all metallic surfaces associated therewith are kept in the upper story away from the lower floor where the loading of explosive is effected. The lower sections 13a of the tamp-rods are preferably made of non-metallic and/or non-pyroscopic material. The sections 13a are secured at their upper ends into metal tubes 13b, which extend through the floor. The metal tubes 13b are in turn secured to square metal sections 13c which extend to the top of the machine. Cross-bars such as the cross-bar represented by 15 are positioned throughout the length of the tamp-rods 13 and serve to guide and space them. The extreme lower end of section 13a of the tamp-rods is tapered and is slightly larger in cross-section at the lower extremity, so that air is permitted to escape when the tamp-rods descend into their respective shells and also to prevent undue suction when the tamp-rods ascend from their respective shells. The lower ends of the tamp-rods 13 work through non-pyroscopic metal nipples 17, which are affixed to the bottom of explosive hopper 19 and penetrate the shells being loaded. The shells are held in a rotatable shell holder 21, provided with shell holding cavities 24a, which rotates about a horizontal axis and reciprocates vertically in cooperation with an appurtenant mechanism (not shown) well-known in the art. It is readily seen that the revolution of the shell holder 21 is to permit each series of shells to be successively and concentrically positioned beneath the tamp-rods 13, while the vertical reciprocation of holder 21 is to permit the holder to be raised when the shells are concentric with the tamp-rods, so that the empty shells (not shown) in the shell holder 21 engage the nipples 17 thereby eliminating any possibility of "losing" explosive during the filling operation. After the shells have been filled, the shell holder 21 is lowered and revolved, and the shells are crimped, closed and ejected by means (not shown) well known in the art, thereby augmenting a continuous mode of operation as empty shells are continuously fed to the shell holder 21. In connection with feeding the explosive to the hopper 19, any suitable means, such as continuous conveyors (not shown) may be employed. In connection with the shell filling operation suitable safe methods for agitating the explosive in the hopper must be provided to insure uniformity in packing the shells. A suitable and well known expedient for accomplishing this purpose is the utilization of mechanical means (not shown) within the explosive hopper 19, whereby friction in the explosive is kept to a minimum.

The apparatus for independent operation of the tamp rods and means for locking any one of them stationary, as soon as its respective shell is filled, without stopping the action of the others will now be described with particular reference to Figs. 1 and 2. Each of the plurality of tamp-rods 13 is reciprocated vertically by cross-head 11 which has a plurality of friction clamp-plates or gibs 23 held into engagement with the tamp-rods 13. These gibs 23 are individually regulated by thumb screws 25 as to give any desired degree of frictional contact to its respective tamp-rod 13. This frictional connection of the tamp-rods with the cross-head causes the latter to reciprocate the tamp-rods, but still leaves them slidably independent thereof, so that they may slide when packing conditions so necessitate. A hand wheel 27 is also provided for general adjustment of the cross-head 11, which is custom-

arily utilized to compensate for temperature variation, thereby rendering it unnecessary to adjust all the thumb screws 25 individually. Below the cross-head 11 there is a dogging device 29 whose function is to lock any one of the tamp-rods 13 as soon as it fills its respective shell and has risen to a point where its action is no longer needed. This function is accomplished by having a plurality of dogging pins 31 slidably secured in the dogging device 29, which are compressively maintained in an operative position by springs 33 respectively, and which operate when a swing bar 35 actuates fluid cylinders 37 to move the dogging device 29 forward so that the dogging pins 31 engage apertured inserts 39 integral with the tamp-rods 13, thereby locking the latter in a fixed position. To disengage the dogging pins 31 from the inserts 39 push rods 41 are actuated by constant pressure fluid cylinders 43 when the swing bar 35 is forward as a result of all of the pins having engaged their respective inserts, and fluid cylinders 37 have been exhausted. This moves the dogging device 29 backward to its inoperative position and, accordingly, the dogging pins 31 assume their respective inoperative positions.

Each time the tamp-rods 13 are raised by frictional engagement with the cross-head 11, they do not all stand, necessarily, on the same level, due to different quantities of explosive having been packed in the various shells. They are brought to the same level, however, before starting on the initial downward stroke by a cushioned correcting bar 45 which in its operative position is disposed directly above the tamp-rods 13 and against which the tamp-rods strike and are leveled just above the cross-head 11 to give a full initial stroke. This causes all of the independent tamp-rods to have an equal advance stroke through the explosive at the initiation of each filling cycle. The correcting bar 45 is moved to its operative position by constant pressure fluid cylinders 47 and is actuated to its inoperative position when increased pressure is supplied to fluid cylinders 49. Cross-head balance cylinders 51 under constant pressure have associated members (not shown) connected to the cross-head 11 and serve to balance the cross-head against frictional and gravitational forces as it reciprocates up and down in guides. A check bar 53 located near the top of the A frames 4 serves to limit the travel of the tamp-rods upwardly under all conditions.

When the shells of the cartridges are packed with explosive, it will be seen that if all the tamp-rods are connected rigidly together, any one of the shells is liable to be filled in advance of the others, and if its tamp-rod continued to act, the explosive would be compressed too hard in that particular shell, while the others would be imperfectly filled; but when the tamp-rods are each independent in their action, whenever a tamp-rod which has filled its shell in advance of the others, rises to a given point, this tamp-rod is locked stationary while all the others continue to work until they have filled their respective shells at which time the same action takes place with them. When the shells are being packed with explosive by successive reciprocation of the tamp-rods, every movement of each tamp-rod packs a definite quantity of explosive into the shell and each tamp-rod must, as the shell becomes filled, rise; but when the cross-head comes down for the next stroke, the tamp-rod is driven down just as far as it had heretofore risen from the growing

bulk of explosive in the shell, therefore it will be seen that when the tamp-rod has reached its extreme height from a perfectly filled shell, at this time only do the tamp-rods come into registry with the dogging pin and are securely locked.

Referring now more particularly to Figs. 3, 4, 5, and 6, the apparatus improvement comprising the present invention will be set forth and as generally described will be referred to as a triple-purpose bar. Apparatus for uniformly packing a shell with explosive to form a cartridge has been disclosed above, however, when it is desired to pack a shell having a firm initial portion, a loose central portion and a firm final portion, a dogging element 55 is affixed to each of the tamp-rods 13. A triple-purpose bar 57 is slidably mounted between angle brackets 59, which are affixed to the A frames 1, and the bar 57 engages the dogging elements 55 in a manner hereinafter described. The triple-purpose bar 57 comprises a body member 61 having reinforcing members 63 and 65 affixed to the top and bottom side, respectively, of the body member. Interposed between the reinforcing member 63 and the body member 61 is a cover plate 67. A plurality of 25 spring urged detents 69 each having a compression spring 71 and each of which is adapted to engage its respective dogging element 55, is slidably secured to the body member 61 by bolts 73, sleeves 75, nuts 77, pins 79 and plates 81 which are affixed to the body member by screws 83. Fluid cylinders 85 and 87, affixed to the frames 1, move the triple-purpose bar 57 forward to a position, represented by 57', as limited by the piston stroke of cylinders 85 and 87. Fluid cylinders 89 and 91, adjacent to cylinders 85 and 87 respectively, move the triple-purpose bar further forward to a position, represented by 57'' as imparted by the piston stroke of cylinders 89 and 91 and as limited by the piston stroke of cylinders 93 and 95, adjustably affixed to the frames 1. With forward movement of the bar 57 to operative position 57', latching heels 55a on dogging elements 55 are engaged. When the cylinders 85, 89, and 87, 91 are exhausted, the piston rods 97 and 99, respectively, engage seats 105 and 107, respectively, which are affixed to the bar 57, and the bar is returned to its inoperative position by cylinders 93 and 95. When cylinders 93 and 95 are exhausted and cylinders 89 and 91 are filled with motive fluid, bar 57 moves to the operative position 57'' and latching heel 55b on dogging elements 55 are engaged. The top portion of dogging elements 55 is bevelled and the engaging end of detents 69 is bevelled in a compatible manner so that the latching heels 55a during the ascending stroke of the tamp-rods 13 push the slideable detents 69 backwards as the elements 55 slip by, when the bar 57 is in position 57'.

An example of the operation of the invention is given for packing an eight inch cartridge, wherein it is desired to pack the initial two inches firm, the next four inches loose and the remaining two inches firm. After the tamp-rods 13 have executed a couple of strokes in the conventional manner, whereby the explosive is firmly packed in the bottom two inches of the shell, cylinders 85 and 87 actuated by fluid pressure move the triple-purpose bar 57 to position 57' (Fig. 6). In this position the latching heels 55a on the descending stroke engage the detents 69 of the bar 57 and on the ascending stroke slip by the detents as explained, supra. With the bar 57 in this position, the tamp-rods 13 merely push explosive loosely into the shell without packing it firm. When the 75

explosive has been loosely packed for approximately four inches the explosive builds up to a point where the tamp-rods 13 are again packing firm, due to the fact the latching heels 55a are no longer engaging the detents 69. These latter two inches are, therefore, firmly packed similar to the initial two inches and this firm packing in the end of the cartridge facilitates crimping the ends, whereby such deleterious effects such as, mushroomed ends, telescopic wrinkling, and collapsing of the cartridges are eliminated. When the cartridges have been fully packed, the dogging pins 31 engage the inserts 39 of the tamp-rods 13 in the conventional manner, as explained, supra.

A safety feature, comprising one of the functions of the triple-purpose bar 57 is utilized independent of the other functions, that is, whether soft packing or not. Each time the shell holder 21 drops, fluid pressure is exhausted from cylinders 93 and 95 and cylinders 89 and 91 actuated by fluid pressure, thereby move the bar 57 to safety position 57'' (Fig. 6) whereby the tamp-rods are dogged and cannot enter their respective shells. As soon as the shell holder 21 has turned and has raised so that the shells engage nipples 17, the cylinders 85, 87 and 89, 91 are exhausted and the fluid pressure previously exhausted is again applied to cylinders 93 and 95, and the bar 57 returns to its inoperative position.

There are numerous factors which will influence conditions for the most satisfactory operation of the invention, the actual limits of which cannot be established except by detailed study of each set of materials and the intermediate and finished products involved, however, it is seen that the functions of bar 57 are three-fold and adapted to provide means for automatically soft packing, automatically preventing any tamp-rods from accidentally sticking down in such manner as to interfere with rotation of the shell holder, and manually dogging up the entire set of tamping rods to the inoperative position whenever necessary due to accidents or other exigencies. It is further seen that a method of soft packing cartridges is provided wherein the cartridges are so packed that crimping is accomplished without deleterious distortion in the body of the cartridge.

It will be seen, therefore, that this invention actually may be carried out by the use of various modifications and changes without departing from its spirit and scope.

What we claim and desire to protect by Letters Patent is:

1. In a machine for filling shells having a series of independent tamping rods and driving mechanism frictionally engaging the tamping rods to reciprocate and permit them to independently retrogress as the shells become filled, the improvement which comprises a dogging element affixed to each of the independent tamp-rods; a dogging bar having independent detents adapted to engage the independent dogging elements; means for moving the dogging bar to a first position to engage the dogging elements and restrict downward travel of the tamp-rods into their respective shells; and means for moving the dogging bar to a second position to engage the dogging elements and prevent the tamp-rods from entering their respective shells.

2. In a machine for packing cartridges with explosive having a series of independent tamping rods and driving mechanism frictionally engaging the tamping rods to reciprocate and permit them to independently retrogress as the car-

tridges become filled, the improvement which comprises a dogging element affixed to each of the independent tamp-rods, said dogging element having an upper step and a lower step, the upper step having a beveled top portion adjacent thereto; a dogging bar having independent spring urged detents adapted to engage the dogging elements, each detent having a beveled portion operatively contiguous with the beveled top portion of a respective dogging element, to permit the dogging element to slip by the detent when its respective tamp-rod ascends; means for moving the dogging bar to a first position wherein the detents engage the upper step of their respective dogging elements, thereby restraining the descent of the tamp-rods into their respective cartridges; and means for moving the dogging bar to a second position wherein the detents engage the lower step of their respective dogging elements, thereby preventing the tamp-rods from entering their respective cartridges.

3. In combination with a machine for filling shells a dogging mechanism which comprises a series of independent dogging elements each of

which is affixed to a respective tamp-rod of a series of independent tamp-rods, each of said dogging elements having an upper step and a lower step, the upper step having a beveled top portion adjacent thereto; a dogging bar having independent spring urged detents adapted to engage the dogging elements, each detent having a beveled portion operatively contiguous with the beveled top portion of a respective dogging element, to permit the dogging element to slip by the detent when its respective tamp-rod ascends; means for moving the dogging bar to a first position wherein the detents engage the upper step of their respective dogging elements, thereby restraining the descent of the tamp rods into their respective shells; means for moving the dogging bar to a second position wherein the detents engage the lower step of their respective dogging elements, thereby preventing the tamp-rods from entering their respective shells.
